CORE DRILL

Application filed February 13, 1930. Serial No. 428,210.

This invention relates to new and useful improvements in a core drill.

One object of the invention is to provide a device of the character described whereby samples of the formation being pierced in well drilling may be readily obtained and withdrawn to the ground surface for inspection.

Another object of the invention is to provide, in a device of the character described, a core barrel or sample chamber for receiving the core or sample and which may be readily withdrawn to the ground surface independent of the drill stem and drill and which may be readily inserted through the drill stem and located in position for receiving the core or sample.

A further feature of the invention resides in the provision of apparatus of the character described having a fluid passageway around the core barrel through which the drilling fluid may be supplied to the cutting point of the bit or drill without reaching and contaminating the sample being taken.

With the above and other objects in view the invention has particular relation to certain novel features of construction, operation and arrangement of parts, an example of which is given in this specification and illustrated in the accompanying drawings wherein:

Figure 1 shows a vertical sectional view of the apparatus partly broken away.

Figure 2 shows a cross sectional view taken on the line 2—2 of Figure 1, and

Figure 3 shows a bottom end view of the drill.

Referring now more particularly to the drawings wherein like numerals of reference designate similar parts in each of the figures, the numeral 1 designates a tubular drill stem to the lower end of which a core forming drill 2 is attached by means of the drill collar 3. This drill may be of any selected type and it has the axial bore 4 therethrough to permit the inlet of a sample and the lower end of said bore being slightly reduced to form the inside annular shoulder 5 which forms a support for the tubular core

is fitted into the enlarged portion of the bore 4 and rests on said shoulder.

Screwed into the upper end of the bore 4 and surrounding the barrel 6 there is a cylinder 7 whose upper end is flared forming the annular partition 8 between the core barrel and drill stem, said partition being provided with a plurality of ports as 9. As shown the cylinder 7 is spaced from the stem 1 so as to form a channel 10 having the downwardly diverging outlet ducts 11 through the drill 2 above the side cutters 12.

The core barrel has one or more expandable metal packing rings 13 therearound and above these there are the upwardly opening cup rings 14 also mounted on said barrel. These rings 13, 14 fit closely within the upper end of the cylinder 7 when the core barrel is assembled in place in the apparatus.

When the device is assembled as above explained and as shown in Figure 1 drilling may be proceeded with in the usual way by rotating the drill stem 1 and as the drill 2 pierces the formation a sample of the formation will enter the core barrel. Drilling fluid under pressure may be forced downwardly through the stem 1, the ports 9, channel 10 and outlet ducts 11 to carry away the cuttings from the drill and this flushing fluid will return up through the well bore on the outside of the stem 1. The drilling fluid, however is discharged as is obvious some distance above the inlet end of the port 4 and the fluid will thus be sealed off from entering the lower end of said bore and the cylinder 7 and packing rings 13, 14 will prevent the drilling fluid from entering the core barrel directly so that a practically uncontaminated sample of the formation may be obtained.

The upper end of the core barrel has an outlet passageway 15 controlled by the upwardly opening ball valve 16 which is confined by the cage 17 attached to the upper end of said barrel. The upper end of the cage has conical shaped head 18 thereon.

When a sample has been taken and it is desired to remove the same to the ground surface a fishing tool of conventional construction may be lowered down into the drill stem and engaged over the head 18 and the

core barrel withdrawn to the ground surface. While withdrawing the core barrel the passageway 15 will be closed by the valve 16 and this will ordinarily prevent the core from dropping out although other core retaining means may be provided in the lower end of the barrel if desired. When the core or sample is entering the core barrel the valve 16 will lift to permit the escape of air or fluid 10 in the core barrel above the sample.

The core barrel may be lowered through the stem by a suitable cable connected to the head 18 by means of a detachable fishing tool and its lower end will be guided into the 15 cylinder, by the upwardly flared partition 8, and will finally land on the shoulder 5 with the packing rings 13, 14 in the upper end of the cylinder and said core barrel will be maintained in place by the pressure of the 20 fluid above against said packing rings during operations.

The drawings and description disclose what is now considered to be a preferred form 25 of the invention by way of illustration only, while the broad principle of the invention will be defined by the appended claims.

What we claim is:

1. A sample taking device including a tubular stem, a drilling tool attached to the 30 lower end thereof having an axial bore provided with an inside seat, a core barrel in the stem whose lower end is unattached to, but rests on said seat, a cylinder around said barrel whose upper end is formed into a guide 35 and whose lower end is attached to said drilling tool, packing rings between said barrel and cylinder, said cylinder being spaced from the stem to form a channel for fluid, and said device having a fluid outlet leading from 40 said channel.

2. A sample taking device including a tubular stem, a drilling tool attached to the lower end thereof and having an axial bore, a core barrel in the stem in alignment with 45 said bore and whose lower end is associated with, but unattached to, said tool, a cylinder around the stem and within and spaced from the barrel forming a fluid channel between the cylinder and stem, the upper end of said 50 cylinder being flared and formed with an opening for fluid and the lower end of said cylinder being attached to said tool, said device having an outlet leading from the lower end of said channel, and packing around the 55 barrel and between said barrel and the upper end of said cylinder.

3. A sample taking device including a tubular stem having a cylinder in the lower end thereof spaced from the stem, a drilling tool 60 attached to the lower end of the stem and cylinder and having a bore, the space between the stem and cylinder having a lower end outlet, a sample chamber within the cylinder, and packing means including packing 65 rings and cup rings, forming an approxi-

mately fluid tight joint between the sample chamber and cylinder.

4. A sample taking device including a tubular stem, a drilling tool attached to the lower end thereof and having a bore for the inlet of a sample, a cylinder in the stem whose lower end is anchored to said tool and whose upper end is formed with a perforated partition between said cylinder and stem, a core barrel in said cylinder arranged to receive a sample through said bore, packing around the barrel forming a substantially fluid tight joint with the cylinder, there being a channel for drilling fluid leading from within the stem above said packing and whose lower end terminates on the outside of the 70 device above the inlet end of said bore.

5. A sample taking device including a tubular drill stem, a core forming tool at the lower end thereof, a tubular core barrel in, 75 and removable independently of, the stem whose lower end is associated within said tool said tool having a core receiving inlet opening into the barrel, a cylinder attached to the tool and surrounding the lower end of the barrel and whose upper end is formed with a guide, a packing between the cylinder and barrel, there being fluid passageway leading from within the stem above the packing and terminating on the outside of the 80 device above said inlet.

6. A sample taking device including a tubular drill stem, a core forming tool at the lower end thereof, a tubular core barrel in the stem whose lower end is associated with-

in said tool said tool having a core receiving inlet opening into the barrel, a cylinder attached to the tool and surrounding the lower end of the barrel and whose upper end is formed with a guide, a packing between the cylinder and barrel, there being fluid passageway leading from within the stem above the packing and terminating on the outside of the device about said inlet, said barrel having a valve controlled outlet at its upper 95 end.

7. A core drill having a stem, a core barrel slidable upwardly and downwardly in said stem, said barrel having a core chamber, and a packing on said barrel above said chamber, 100 said packing being radially expansible until its external diameter is greater than the external diameter of said barrel.

8. A core drill having a stem, an inner tube in said stem, a core barrel slidable in said 105 stem downwardly into and upwardly out of said tube, said barrel having a core chamber, and a radially expansible packing on said barrel above said chamber to seal the space between said barrel and tube.

9. A core drill having a stem, a core barrel slidable upwardly and downwardly in said stem, said barrel having a core chamber in its lower end, a reduced portion above said 115 chamber, and a packing on said reduced por-

tion, said packing being radially expandible until its external diameter is greater than the external diameter of said barrel.

10. A core drill having a stem, an inner tube in said stem, a core barrel slidable in said stem downwardly into and upwardly out of said tube, said barrel having a core chamber in its lower end, a reduced portion above said chamber, and a radially expandible packing on said reduced portion to seal the space between said barrel and tube.

11. A core drill having a stem, a bit on the lower end of said stem, an inner tube spaced within said stem and extending upwardly from said bit, a core barrel slidable in said stem downwardly into and upwardly out of said tube, said barrel having a downwardly opening core chamber and a reduced portion above said chamber, and a packing on said reduced portion to seal the space between said barrel and tube.

12. A core drill having a stem, a bit on the lower end of said stem and having a fluid duct therethrough, an inner tube spaced within said stem and extending upwardly from said bit, the space between said tube and stem forming a slush passageway in communication with said duct, a core barrel slidable in said stem downwardly into and upwardly out of said tube, said barrel having a downwardly opening core barrel and a reduced portion above said chamber, and a packing on said reduced portion to seal the space between said barrel and tube.

35. In testimony whereof we have signed our names to this specification.

GEORGE J. BARRETT.
SOSTHENE ROBICHAUX.
